Atty.

UNITED STATES PATENT OFFICE.

FREDERICK C. WHITE, OF CHICAGO, ILLINOIS.

APPARATUS FOR PRINTING FROM PHOTOGRAPHIC NEGATIVES.

SPECIFICATION forming part of Letters Patent No. 764,090, dated July 5, 1904.

Application filed March 28, 1904. Serial No. 200,465. (No model.)

To all whom it may concern:

Be it known that I, FREDERICK C. WHITE, a citizen of the United States, and a resident of Chicago, in the county of Cook and State 5 of Illinois, have invented certain new and useful Improvements in Apparatus for Printing from Photographic Negatives, of which the following, when taken in connection with the drawings accompanying and forming a part 10 hereof, is a full and complete description, sufficient to enable those skilled in the art to which it pertains to understand, make, and use the same.

This invention relates to mechanism by 15 means of which a photographic negative, particularly when such negative is on a "film," as it is termed in the art, can be readily and easily handled in the printing therefrom of photographic positives; and, further, it relates to mechanism by means of which a border of a determined width may be 20 placed on the positive print in proper relation to the view or picture printed thereon from the negative used.

The object of this invention is to obtain an 25 apparatus for the purpose set forth which may be made and used by persons reasonably skilled in the art of photography.

A further object of the invention is to obtain an apparatus for the purpose set forth 30 which can be economically constructed by the person desiring to use the same, as well as by manufacturers thereof for sale, which is simple, durable, and not liable to be broken or otherwise injured and by means of which the 35 party using the same can readily obtain prints, from film-negatives particularly, which will be neat and clean in appearance.

An apparatus embodying this invention is illustrated in the drawings accompanying and 40 forming a part of this specification, hereinafter referred to, and in which—

Figure 1 is a top plan view of a templet used in making the print-controlling portions of the apparatus embodying this invention 45 with a glass plate thereon. Fig. 2 is a cross-

section of the templet illustrated in Fig. 1 on line 2 2 thereof viewed in the direction indicated by the arrows with the glass plate which is shown in Fig. 1 removed. Fig. 3 is a top plan view of a gage for printing a 55 border from a negative formed by such gage, such gage being made on the templet illustrated in Figs. 1 and 2. Fig. 4 is a cross-section of the gage illustrated in Fig. 3 on line 4 4 of such Fig. 3 viewed in the direction indicated by the arrows. Fig. 5 is a top plan view of a combined film-holder and gage made on the templet illustrated in Figs. 1 and 2. Fig. 6 is a cross-section of the combined film-holder and gage illustrated in Fig. 5 on lines 65 6 6 of such Fig. 5 viewed in the direction indicated by the arrows. Fig. 7 is a top plan view of an ordinary printing-frame used by me as an element in the operation of the apparatus embodying this invention. Fig. 8 is 70 a side elevation of the back of the printing-frame which is illustrated in Fig. 7; and Fig. 9 is a view of a print obtained from a negative film by means of the apparatus embodying this invention, showing a border obtained 75 from the combined gage and negative illustrated in Figs. 3 and 4.

A reference-letter applied to designate a given part is used to indicate such part wherever the same appears throughout the several 80 figures of the drawings.

A is a templet and comprises body part *a*, rail *a'*, extending along two of the sides of body *a*, and a locking device or part, which preferably consists of the wedges *a*² *a*², firmly 85 secured to the body part *a*, and the movable wedges *a*³ *a*³, engaging with the wedges *a*² *a*², respectively, and the sheet of glass B, Fig. 1, which is secured in place thereby on templet A with its edges which are adjacent to the 90 rail *a'* closely in contact therewith.

C C, C' C', and D D are respectively lines or marks on the body *a* of templet A. The several squares obtained by the intersection of the lines C C are of a size to correspond 95 with one size of photographic films or plates, and the squares obtained by the intersection of the lines C' C' are of size to correspond with a different size of photographic films or plates. As many of such lines C C C' C' may 100

be placed on the templet as desired in order to obtain additional squares for different-size films. The square obtained by the lines D D is used for making the combined holder and gage illustrated in Figs. 5 and 6 and hereinafter described when it is desired to obtain, in a print made from negatives by the use of this apparatus, a view or picture not extending closely to the border obtained by the use 10 of the gage illustrated in Figs. 3 and 4.

E, Figs. 3 and 4, is a combined negative and gage and consists of glass plate e, cover e' e' e' to such glass plate, and projecting lugs e' e' on the side of the glass opposite to the 15 cover e' e' e'.

e' is an opening between the part e' of the cover of plate e and part e' e' of such cover.

To make the combined gage and negative E, a piece of clear glass, as B, Fig. 1, is placed 20 in templet A and secured firmly in position, as by wedges a' and a'. A sheet of gummed paper of a color not permitting actinic rays to pass therethrough, as, say, black, of a size as large or larger than the portion of the film 25 or negative which is to be printed by the use thereof is then made to adhere to the sheet of clear glass, the position of such gummed paper on the clear glass being determined by the lines C C or C' C' or other like lines on 30 templet A. In Figs. 3 and 4 the gummed paper e' is of the proper size to be used in making a print of the size laid out by lines C' C' of Fig. 1. A larger piece of gummed paper e' would be used to make a print of 35 about the size of the square formed by the lines C C of such Fig. 1. In practice I prefer to make the sheet of gummed paper e' before it is gummed to the glass B larger than it is to ultimately be and to secure such 40 larger sheet on the glass to overlap the square made by the lines, as, say, C' C', and after the same is firmly attached to the glass to cut it down by means of a knife and a straight-edge to the size of the square made by such 45 lines, as I thus insure not only the exact position to the part e' on the glass B, but also the exact size thereof, so that the same will properly register with the gage and holder illustrated in Figs. 5 and 6 and hereinafter 50 described. After the gummed piece e' is secured firmly in position and made of proper size the strips e' e' (indicated by dotted lines in Fig. 3) of gummed paper may be successively attached to the glass B in position to leave the 55 clear-glass opening e', and then the part of the cover e' may be gummed in place. Strips e' e' may be gummed in place at any suitable distance from the several edges of the part e' and parallel thereto, the width of the clear- 60 glass opening corresponding with the desired width of the border. (See Fig. 9, border F.)

G G' G² are marks made, respectively, on the templet A, the combined gage and negative E, and the printing-frame X to indicate 65 the relative position which such parts should

at all times have with each other in the making and use of the apparatus.

The lugs e' e' are placed on the gage E so that when such gage is in the printing-frame the outer edges of such lugs will be in contact 70 or close to contact with the respective edges of the front opening of the printing-frame, such edges of the printing-frame being indicated by broken lines X' X' in Fig. 7, to hold the edges of the gage adjacent to the mark G² 75 on the printing-frame in close contact with such edges.

H is a combined film-holder and gage, Figs. 5 and 6, made on the templet A in the following manner: A sheet of clear glass is placed 80 in position on templet A in the same manner as is done to make the combined negative and gage E. Assuming that the combined film-holder and gage H is to be used in conjunction with the combined negative and gage E 85 for the printing of a photographic positive, a gummed-paper covering is placed on the sheet of glass, with an aperture therein corresponding in position and size with the portion e' of the combined negative and gage E or corre- 90 sponding in position and size with the square formed by the lines D D in Fig. 1. When the aperture in the gummed-paper covering of the combined holder and gage H is made of the same size as the part e' of the cover of 95 gummed paper on combined negative and gage E, the picture printed from a negative when this apparatus is used will extend to the border obtained, as is illustrated in Fig. 9, and when such aperture is of the size to correspond to the square made by the lines D D in 100 Fig. 1 the picture will not extend to the border F F, the space between such picture and border being equal to the space between the square made by the lines D D and the square 105 made by the lines C' C' in Fig. 1.

In making the combined holder and gage H, I prefer to successively attach strips of gummed paper, as h h' h' h', to the glass, and after such strips have all been gummed in 110 place, with the inner edges thereof corresponding with the lines C' C', the flaps h' h', of paper or thin cardboard, are attached in place, as by gumming them. The inner edges of the flaps h' h' engage with the edges of the film-negative from which the print is to be obtained, such edges coming underneath the edges of the flaps, as is indicated by the broken lines I I in Fig. 5. Broken lines I I indicate 115 the negative, either on film or glass, which may be used with the combined negative and gage E and the combined holder and gage H to obtain a picture—as, say, the photographic print illustrated in Fig. 9.

h' h' are lugs on the combined holder and 125 gage H, corresponding in position and function with the lugs e' e' on combined negative and gage E.

J, Figs. 7 and 8, is the back to the printing-frame X. This back is composed of two 130

parts j j' , joined by the hinges j^2 in the ordinary way and provided with the ordinary springs K K.

5 L are projecting lugs, usually of metal, on frame X, with which the springs K K are brought into engagement to hold the paper on which the photographic print is to be made in close contact with the negative used.

Where the combined holder and gage H is 10 used for holding a photographic film, the thickness of the covering of such combined holder and gage—that is, the thickness of the several strips h h' h^2 h^3 —tends to hold the film off from contact with the photographic-printing paper, and in order to force such film down to close contact with the paper or to force the printing-paper closely against the negative film I place pieces M M, Fig. 8, on the under side of the parts j j' of the back J. 15 Such pieces may consist of cardboard of substantially the same thickness as the combined thickness of the cover and flaps of the combined holder and gage H.

The manner of the operation of this apparatus is as follows: The combined negative and gage E is placed in the printing-frame X with the covered side thereof toward the back of the printing-frame. A sheet of photographic-printing paper is placed against such 20 negative and gage with two of its sides in contact with the sides of the printing-frame corresponding with the rails a a' of templet A and the back J is placed in the printing-frame and secured against the paper in the usual way. 25 Such paper is then exposed to a suitable light for a proper length of time. The paper and the combined negative and gage are then removed from the printing-frame, and the combined holder and gage H, with a photographic film 30 therein, is put into the printing-frame with such film on the side of the combined holder and gage which is adjacent to the back J. The printing-paper which has been exposed on the combined negative and gage E is then placed 35 in position in the printing-frame on the combined holder and gage and on the negative film held therein with the two of its sides which were in contact with the sides of the printing-frame when such printing-paper was 40 placed over the combined negative and gage again brought into contact with such sides, and thereby such paper registers with the holder in gage H and with the printing-frame in the same manner as when placed in such 45 printing-frame with the combined negative and gage E. The back J is then placed in the printing-frame and secured in position to hold the printing-paper against the negative film. Pieces M M press such printing-paper firmly 50 against the film. The printing-paper is then again suitably exposed to a light. The paper is then taken from the printing-frame and developed in the ordinary way.

Having thus described my invention, its con-

struction, and manner of use, what I claim as new, and desire to secure by Letters Patent, is—

1. A templet, consisting of a body part, rails on two adjacent sides of the body part, and means to secure a plate of glass against such rails, such body part provided with intersecting lines to form a rectangle; substantially as described.

2. A templet consisting of a body part, rails on two sides thereof and means to secure a plate of glass against such rails, such body part provided with intersecting lines to form a rectangle, in combination with gages, one of such gages consisting of a plate of glass having a central covering on one side thereof, such covering registering with a rectangle on the body of the templet and a marginal covering having the inner edges thereof related to the outer edges of the central covering, and the other of such gages consisting of a plate of glass having a covering on one side thereof provided with a central opening therein registering with the rectangle on the templet; substantially as described.

3. A templet consisting of a body part, rails on two adjacent sides thereof and means to secure a plate of glass against such rails, such body part provided with intersecting lines thereon, in combination with gages, one of such gages consisting of a plate of glass having a central covering thereto registering with intersecting lines on the body of the templet and a marginal covering having the inner edges thereof related to the outer edges of the central covering, and the other of such gages consisting of a plate of glass having a covering on one side thereof provided with a central opening therein, such opening registering with the rectangle formed on the templet by the intersecting lines, and flaps on the last-named gage to engage with a photographic-negative film; substantially as described.

4. A templet consisting of a body part, rails on two adjacent sides thereof and means to secure a plate of glass against such rails, such body part provided with intersecting lines thereon, in combination with gages, one of such gages consisting of a plate of glass having a central covering thereto registering with intersecting lines on the body part of the templet and a marginal covering the inner edges of the opening therein related to the outer edges of the central covering, and the other of such gages consisting of a plate of glass having a covering on one side thereof provided with a central opening therein, such opening registering with the rectangle on the templet with which the central covering of the first-named gage registers, flaps on the last-named gage to engage with a photographic-negative film, a printing-frame, the removable back whereof is provided with a raised

portion registering with and fitting against the negative film in the combined holder and gage; substantially as described.

5. A templet consisting of a body part, rails 5 on two adjacent sides thereof, means to secure a piece of glass against such rails, and such body part provided with intersecting lines thereon, in combination with gages, one of such gages consisting of a piece of glass having 10 a central covering thereto registering with intersecting lines on the body of the templet and a marginal covering having the inner edges thereof related to the outer edges of the central covering, and the other of such gages 15 consisting of a piece of glass having a covering thereto provided with a central opening, such central opening registering with the rectangle obtained by intersecting lines on the body of the templet and with which the 20 central covering of the first-named gage registers, and flaps on the last-named gage to engage with a photographic-negative film, a printing-frame provided with a removable back, and a raised portion to the removable 25 back, such raised portion registering with the negative film held in the combined holder and gage; substantially as described.

6. A combined negative and gage, consisting of a plate of glass provided with a central 30 covering and a marginal covering the inner edges whereof are related to the central covering, in combination with a combined holder and gage consisting of a glass plate provided with a marginal covering, the central opening 35 in such covering registering with the central covering of the first-named negative and gage, and flaps attached to the marginal covering to engage with a photographic-negative film; substantially as described.

7. A combined negative and gage, consisting of a plate of glass provided with a central covering and a marginal covering the inner edges of such marginal covering related to the edges of the central covering, in combination with a combined holder and gage consisting of a glass plate provided with a marginal covering, the central opening in such covering registering with a central covering of the combined negative and gage, and flaps attached to the marginal covering, to engage 45 with a photographic-negative film, and a printing-frame provided with a removable cover and a raised part to such cover such raised part registering with the central opening in the combined holder and gage, and the combined 50 holder and gage, the combined negative and gage and the printing-frame respectively provided with corresponding marks to identify corresponding sides; substantially as described. 55

8. A templet consisting of a body part, rails on two adjacent sides thereof, means to secure a piece of glass against such rails, and such body part provided with intersecting lines thereon to form a rectangle, in combination with a combined holder and gage consisting of a plate of glass provided with a marginal covering, the central opening in such covering registering with the rectangle on the templet, and flaps attached to the marginal 65 covering to engage with a photographic-negative film, with corresponding marks on the templet and the combined holder and gage; substantially as described. 70
